ATTORNEY

UNITED STATES PATENT OFFICE

GOLIAT DAVISON, OF ST. LOUIS, MISSOURI

FUR SCARF HANGER

Application filed May 4, 1929. Serial No. 360,358.

My invention relates to improvements in a fur scarf hanger, and has among its objects, the production of such a hanger which shall be simple, neat and attractive in appearance, 5 economically made, easy to put on or take off the scarf, and efficient and satisfactory for use wherever found applicable.

Many other objects and advantages of the construction herein shown and provided will 10 be obvious to those skilled in the art to which this invention appertains, from the disclosures herein given.

To this end, my invention consists in the novel construction, arrangement and combination of parts herein shown and described, and uses mentioned, and more particularly pointed out in the claims.

In the drawing, wherein like reference characters indicate like or corresponding 20 parts throughout the views,

Figure 1 is an elevation of my improved device, substantially full size; and

Figure 2 is a similar view of the same as used in connection with a fur scarf.

As friction is very harmful to furs, it is highly desirable that the amount of friction which the furs are subjected to be reduced as much as possible. Of course, the friction caused by wearing the fur is unavoidable, but 30 that caused while the fur is out of use and hung away can be reduced, to the end that the longevity of such furs are greatly increased. My invention provides for a device that is intended to be attached to one end 35 of the fur scarf, whereby the scarf may be suspended or supported from said end, not only preventing friction between the fur and support, but permitting the air to come into contact with the fur at every point, further 40 adding to its life and keeping it in perfect appearance and shape.

Referring more particularly to the drawing, wherein I have illustrated a preferred embodiment of my invention, A indicates a 45 fur scarf or choker, the same being provided at one end of the same with a clip fastener, jaw spring or the like, whereby the other end of the scarf may be clamped or gripped to hold the scarf in place while on the person.

Such fastener means includes a bar piece 1, pivoted intermediate its ends, as at 2, to the rest of the fastener structure. A spring or other suitable means is generally provided for normally urging one of the ends, as for example the outermost or uppermost end of the bar piece, into clamping position, so that when releasing the piece from clamping position it is necessary to press downwardly 55 upon the other or innermost end of the 60 piece 1.

The hanger is preferably of a single piece of material, preferably flexible, such as of leather, fibre board, heavy fabric, or the like, 65 of elongated shape, as at 3.

The strip of material is provided with a pair of openings 4 and 5, intermediate its ends, said openings being spaced apart longitudinally along the hanger strip. The openings are substantially of the same maximum width, the opening 4, which may be termed the uppermost opening, as it is uppermost when the hanger is in its supporting or suspending position as shown, being of uniform 70 width, but the lowermost opening 5 preferably being tapered so as to gradually decrease in its width toward its upper portion, said opening 5 thus formed being somewhat triangular in shape.

When positioning the hanger to suspend the fur-scarf, the opening 4 is first placed over the outermost end of the elongated fastener bar 1, said bar being pivotally actuated if necessary, so as to permit the opening 4 to slip past said end of the bar 1. The hanger strip is then pulled down until the bottom edge of the opening 5 passes the lowermost or innermost end of the bar 1, as shown in the dotted line position in Fig. 2, whereupon the lower end of the strip is pressed inwardly 80 past the plane of the bar 1, and the strip is then pulled upwardly a short distance, the hanger then being in the full-line position 85 shown in Fig. 2, in which position it is ready to be hung or suspended. When it is desired 90 to withdraw the scarf from its suspended position, the reverse movement relatively of the hanger, is gone through, the hanger strip being pulled downwardly until the opening 95 5 may be free of the lower end of the bar 1, 100

as indicated in the dotted lines in said Figure, after which the other opening 4 is in succession released from the bar. The pin 2 upon which the bar 1 is pivoted, forms a stop in both directions of longitudinal movement 5 of the hanger relatively of the fastener means.

By making the opening 5 of such substantially triangular shape, the hanger strip is sufficiently flexible thereat for the desired 10 function, and yet there is a proper amount of frictional contact between the strip and the bar 1 to cause the scarf to be held in its desired supported position without accidental movement therebetween which might wear 15 the scarf unnecessarily thereat.

A tab portion 6 may be provided below the opening 5, this portion being of suitable 20 length so as to be easily engageable by the fingers. Any suitable means may be used for suspending the hanger strip from above, such as the hook 7 or the like, the kind and 25 shape of suspending means 7 depending upon the particular point of support with which it will co-operate.

Having thus described my invention, it is 30 obvious that various immaterial modifications may be made in the same without departing from the spirit of my invention; hence I do not wish to be understood as limiting myself to the exact construction, form, 35 arrangement and combination of parts herein shown and described, or uses mentioned, except as limited by the claims.

What I claim as new and desire to secure 40 by Letters Patent is:

1. A hanger for a fur scarf provided with a snap fastener at one end, said hanger comprising a strip of material having a pair of 45 longitudinally spaced openings thereon, said openings being adapted to successively receive the opposite ends of the snap fastener, and means independent of and above said openings for suspending said hanger from a support.

2. In combination with a fur scarf having a clip fastener with oppositely directed ends, a hanger having a pair of spaced openings each receiving one of the ends of said clip fastener to secure the latter and hanger together, whereby said hanger may be suspended so that said scarf will depend therefrom.

3. In combination with a fur scarf having a clip fastener with oppositely directed ends, 55 a hanger comprising a perforated flexible strip of material, both of said ends of said clip fastener being inserted through the perforated portion of said strip to secure said fastener and hanger together, whereby said hanger may be suspended so that said scarf will depend therefrom.

4. A hanger from which fur pieces provided with clasps are adapted to be suspended, said hanger including an elongated strip 65 having an opening adjacent its lower end and

a second opening above and contiguous to the first opening, said openings receiving opposite ends of said clasp, and the part of the strip above the second opening affording a gripping surface for the members of said 70 clasp, and means above the second opening for suspending the strip from a support.

5. A hanger from which fur pieces provided with clasps are adapted to be suspended, said hanger including a strip having 75 spaced openings in its lower portion for receiving the opposite ends of a clamping member of said clasp, and means above said openings for suspending said strip from a support, the portion of the strip between said 80 means and the adjacent opening providing a gripping surface for the clamping members of said clasp.

6. A hanger for fur pieces and the like provided with clamping jaws, said hanger including a flexible strip having openings therein spaced apart a distance less than the extremities of one of said jaws to receive the opposite ends thereof and suspend said fur piece from the strip.

7. A hanger from which a fur piece provided with a clasp of co-operating jaws is to be suspended, said hanger including an elongated strip having an opening adjacent its lower end and a second opening above and contiguous to the first opening, said openings receiving the opposite ends of one of said jaws and spaced apart a distance less than the length of said jaw, and a gripping portion 90 on said strip above the second opening and receiving both of the co-operating jaws of said clasp on the opposite faces thereof.

8. A hanger from which fur pieces provided with clasps with clamping members are adapted to be suspended, said hanger including an elongated strip having an opening intermediate its ends and a second opening spaced thereabove, said openings together receiving the opposite ends of a clamping member of said clasp, that part of the strip above the second opening receiving said clamping members on the opposite sides thereof and gripping thereagainst, and the lower edge of the first opening engaging another portion of one of said clamping members and forming a support for the clasp, and means above said lower opening for suspending said strip from a support.

GOLIAT DAVISON.
